UNITED STATES PATENT OFFICE.

ALBERT E. HENDRICKS, OF CHICAGO, ILLINOIS, ASSIGNOR TO KING PNEUMATIC TOOL COMPANY, OF CHICAGO, ILLINOIS, A CORPORATION OF ILLINOIS.

THROTTLE VALVE FOR PNEUMATIC TOOLS.

Application filed September 10, 1923. Serial No. 661,936.

This invention relates to throttle valves for controlling the admission of motive fluid to pneumatic tools or the like.

Among other objects, the invention is intended to provide a practicable, reliable and efficient throttle valve of the class stated.

10 The invention will be clearly understood by reference to an illustrative structure containing an embodiment of the invention, shown in the annexed drawings, in which:

Fig. 1 is a vertical section of the illustrative structure, showing the throttle valve in normal or released position.

15 Fig. 2 is a similar view of the valve-containing portion of said structure showing the throttle valve in active position.

Fig. 3 is a detail elevation of a movable throttle valve member.

20 Fig. 4 is a similar elevation of said valve member, viewed from the opposite side.

Fig. 5 is a horizontal section of said valve member taken on the line 5—5 of Fig. 4, indicating the size of the throttle valve ports when said member is moved slightly from 25 normal position.

Fig. 6 is a horizontal section taken on the section line 6—6 of Fig. 4, and indicating the size of the throttle valve ports when in full open position.

30 The illustrative structure comprises a throttle valve casing represented by a pneumatic tool handle 1.

Said tool handle is shown, for example, 35 extending from a conventional form of handle base 2 which is adapted to be screwed upon or coupled with the barrel of the tool.

40 A passage 3 in the handle conducts motive fluid from a source of supply to the operating mechanism of the tool. The inlet end of said passage, interiorly threaded for connection with a compressed air supply pipe, is designated at 4. Distribution ports, leading from said passage to the valve mechanism housed in the handle base, are designated at 5.

45 The throttle valve of the illustrative structure is interposed in the passage 3 and controls the flow of the motive fluid between the inlet and distribution branches of said 50 passage.

Said throttle valve comprises a movable valve member represented by a rod or stem 6, and a valve-seat member represented by a short sleeve or bushing 7 in which the rod 55 has a sliding fit.

Said bushing 7 divides the throttle chamber into what may be termed a pressure inlet chamber 8 and a working pressure chamber 9. In this instance, said chambers 8 and 9 are in wide open communication with the inlet and distribution branches of the passage 3 through the handle, and may be considered as exemplifying either distinct chambers in communication with said branches of the passage or as substantially 60 the portions of said passage 3 at the opposite sides of the throttle valve.

65 Throttle valve ports are represented by longitudinal grooves 10 in the valve member 6. The relation of these grooves, the valve member 6, and the bushing 7 is such that at one end of the path of movement of the valve member 6, the latter prevents the passage of motive fluid through the bushing. As the valve member 6 is moved from closed position a gradually increasing 70 passage of motive fluid occurs through these ports until the valve is in completely open condition. These grooves may be conveniently formed by milling out parts of the 75 valve member and are shown extending longitudinally of that member with their axes in parallel relations.

80 For varying the capacity of the valve and for determining its sensitiveness of control 85 of the passage of motive fluid therethrough, the number of the grooves 10 may vary according to the needs of actual practice, but experiments have shown that the number formed in the illustrative embodiment of the 90 invention is suitable and effective to admit of a sufficient flow of the motive fluid, and an adequate control of its passage for operating pneumatic tools. To facilitate a 95 very gradual admission of motive fluid through the valve, these grooves are shown so arranged that their lower ends are located at different distances from the end of that member. An effective arrangement of this kind is one in which the grooves have 100 their lower ends so positioned that a line passing progressively through the centers of those ends will be substantially spirally related to the surface of the movable valve member.

105 With such a spiral arrangement of the lower ends of the grooves, the ports are progressively opened to allow passage of motive fluid past the bushing 7. As the movable valve member is moved through the bushing, 110

the lower end of one of the grooves first presents a passage and the remaining grooves function successively to produce a cumulative passage of motive fluid as the movable valve member is moved further in the same direction past the bushing. Thus, if the operator desires a slow or light operation of the tool he may hold the movable valve member in such a position that only one of the grooves is functioning to permit the passage of motive fluid, and by appropriate adjustment of the tool he may increase the operation as desired. The speed of operation of the tool and the intensity of the result effected by its operation may have a number of degrees of control dependent upon the specific formation of the valve member, and the number of ports therein, as hereinbefore mentioned.

20 A gradual admission of motive fluid through the throttle casing and through the accompanying tool is further ensured by the formation of the grooves. They are shown deepest and widest at their central portions, or about midway of their lengths, and their depth and width gradually decrease as either end is approached, the depth approaching zero at the ends. Thus, as the movable valve member is first moved from closed position, only a minute passage is presented below the bushing 7 for the movement of the motive fluid therethrough. Further movement in the same direction causes a gradual increase in the size and capacity of that passageway so that the speed of operation of the tool and the intensity of its effort is greatest when the groove is so located that its mid-portion is substantially coincident in position with part of the bushing.

25 To facilitate the passage of motive fluid past the bushing, the latter is shown bevelled or cut away at its upper and inner edge. A valve constructed as described permits nicely of control in the admission and flow of motive fluid to the tool, and is adapted to be easily operated. It also affords an effective type of closure when in valve closing position. By employing a valve in the form of a rod which works in a bushing or sleeve and is provided at opposite sides with the longitudinal grooves for the passage of motive fluid, the valve will work without undue friction, there being no unequal lateral pressure on the rod constituting the valve and no binding by pressure of the valve to its seat.

30 This arrangement enhances the sealing effect of the valve in closed position and is conducive to long-continued use of the structure without frequent repairs.

35 As has been previously mentioned, the movable valve member is arranged to operate between the inlet and the distribution branches of a passage extending through the casing. An appropriate arrangement of this kind is illustrated, in which the valve rod

6 is slidably fitted in a bore intersecting the passage 3. This bore is shown provided by a bushing 11 which is fitted within the throttle casing at the working pressure side of the throttle chamber.

For cooperation with the movable valve member and the bushing above described, a check valve is provided, represented by a ball 12. Among other results this check valve or ball 12 serves the purpose of further ensuring the prevention of the leakage of motive fluid when the primary valve parts are in valve closing position. In the construction shown, this ball check valve 12 seats against the bushing 7 and is adapted to be displaced by the valve member 6. The arrangement is such that the check valve is closed soon after the movable valve member has reached its own closed position. This involves the spacing of the check valve a short distance from the groove having one end nearest the end of the movable valve member. In this instance, the ball 12 fits within a socket in the end of the member 6 so as to thereby be held centered with respect to that member.

In order that the ball 12 may move simultaneously with the movable valve member or rod 6, the ball is urged against the end of the latter by a resilient member herein shown as a coiled spring 13. This spring also acts to force the ball against the inner and lower edge of the bushing 7 when the former is permitted to reach one end of its path of movement, and when the ball is so seated it acts as an additional seal to prevent leakage of motive fluid, as above mentioned. One end of the spring 13 contacts with the ball and the other end acts against an abutment herein shown as a screw plug 14.

In the construction shown, the screw plug 14 not only serves the purpose of an abutment member for the spring 13, but also forms a convenient closure for the chamber in which the valve parts are located. The plug is mounted in the throttle casing in such a position as not to interfere with the use thereof. By removing the plug the valve parts are accessible for convenient inspection, repair or disassembly.

The spring 13 of the illustrative structure is utilized to urge both the valve member 6 and the check valve 12 into valve closing condition; and, in order to open the valve, means is provided for moving the above mentioned parts in an opposite direction. Such means is represented by a conveniently located lever 15, pivotally mounted upon the fulcrum member 16 supported by the tool handle, and acting upon the opposite end of the rod 6. A portion of this lever is arranged within the path of movement of the rod 6 so as to actuate the same against the force of the spring. In order that this lever may be substantially inclosed by the throttle

casing, a slot 17 may be bored in the upper surface of the latter and the fulcrum member 16 may pass therethrough.

To prevent sharp movement of the lever 5 from being communicated to the rod 6 so as to allow a sudden inrush of motive fluid causing the tool to be set into operation instantly at a rapid rate, cushioning means is interposed between that part of the lever 15 which extends into the path of movement of the rod, and the rod 6 itself. This cushioning means may be located in a socket 18 bored in the upper end of the rod, and, in the present instance, consists of a cap 19 which is capable of movement relative to the rod and held normally spaced from the latter by a resilient element herein shown as a spiral spring 20. This cushioning means, as above indicated, acts to further ensure a gradual and even movement of the port controlling member when moved to open the valve.

The structure described provides a throttle valve which is extremely sensitive in operation, automatically closing when not in use, and capable of permitting the passage therethrough of a desired amount of motive fluid per unit of time to effectively operate the tool to which it is applied. Such a throttle valve enables the operator to use the tool with different motive fluid pressures so as to maintain any desired character of impact, i. e., light or heavy as desired, and thus renders the tool effective under widely varying conditions.

The operation of the entire throttle valve will be apparent to those skilled in the art, from the previous description, considering the throttle casing to be connected on one side to a source of motive fluid, and on the other, to a tool to be operated. The valve is capable of withstanding constant use under high pressure without excessive wear, and its moving parts are reduced to a minimum.

The valve is susceptible of economical manufacture by reason of the simplicity of its structure, and may be assembled in a pneumatic tool without the prior assembly of the parts in specially constructed sleeves, as has been necessary in ordinary practice. Its manufacture involves a minimum of precise machine work and therefore results in the completion of a maximum number of the completed valves within a fixed period.

Use of the illustrative structure has demonstrated its efficiency in pneumatic tools. The assembly and disassembly of the valve is readily effected for the purposes of repair or replacement of parts. Furthermore the valve is susceptible of convenient design in

order that it may be used in handles of different types of conventional pneumatic tools which use has proven to involve distinct advantages.

Obviously the present invention is not limited to the specific embodiment herein shown and described. Moreover it is not indispensable that all of the features of the invention be used conjointly since they may be advantageously used in various different combinations and sub-combinations.

Having described my invention, I claim:

1. A throttle valve of the class described comprising, in combination, a throttle chamber; a partitioning sleeve therein; a valve 75 comprising a rod slidable through said sleeve and normally closing the same; said rod having ports normally located wholly at one side of said sleeve and adapted upon movement of the valve to active position to 80 establish communication between the opposite sides of said chamber; a check valve opposing movement of said rod from normal position, said check valve adapted to be unseated by said rod; and means for operating 85 said valve rod against the opposition of said check valve.

2. A throttle valve of the class described comprising, in combination, a throttle chamber; a partitioning sleeve therein; a valve 90 comprising a rod slidable through said sleeve and normally closing the same; said rod having ports normally located wholly at one side of said sleeve and adapted upon movement of the valve to active position to 95 establish communication between the opposite sides of said chamber; a check valve comprising an independent ball seated against said sleeve; a spring acting upon the ball and thereby indirectly acting against the 100 rod to maintain the throttle valve closed; and means for operating said rod against the opposition of said ball and spring.

3. A throttle valve of the class described comprising, in combination, a throttle casing 105 having a passage for motive fluid; a movable throttle valve member and a cooperating check valve controlling said passage; the said check valve arranged to be unseated by the movement of said movable valve member; said movable valve member acting to cut off the ingress of motive fluid when in one position, and to present gradually increasing port capacity for the inlet of motive fluid as it is moved in one direction from 110 that position.

In testimony whereof, I have signed my name to this specification.

ALBERT E. HENDRICKS.
